UNITED STATES PATENT OFFICE.

WILLIAM EDWARD TRAYLOR, OF FORT SMITH, ARKANSAS.

LIQUID REGISTER.

Application filed October 9, 1925. Serial No. 61,515.

This invention aims to provide a novel means whereby, at a glance, the value of an amount of liquid drawn out of a tank, may be ascertained.

It is within the province of the disclosure to improve generally and to enhance the utility of devices of that type to which the invention appertains.

With the above and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the drawings:—

Figure 1 shows in section, a device constructed in accordance with the invention; Figure 2 is an elevation showing the casing or support; Figure 3 is a vertical section of the casing or support; Figure 4 is a transverse section taken through the support or casing; Figure 5 is a view showing certain of the pulleys or drums; Figures 6 and 7 are fragmental plans showing the charts.

The numeral 1 marks a support in the form of a tubular casing, connected by a bracket 2 to a measuring tank 3, although the casing 1 might be supported otherwise. A tubular guard 4 extends between the upper part of the casing 1 and the upper part of the measuring tank 3. In its opposite sides, the casing has large, vertically elongated openings 5. There are smaller openings 6 in the casing 1, located above the large openings 5. The openings 5 and 6 may be covered by transparent plates 7 mounted in the casing 1. A first roller 8 is journaled in the casing 1 at one corner thereof, as shown in Figure 4. A second roller 9 is journaled in the casing 1 in diagonally opposite relation to the roller 8. The rollers 8 and 9 may be called receiving rollers, because the charts or tapes hereinafter described, are wound about them. A guide roller 10 is mounted in the casing 1 opposite to the roller 9. The guide roller 11 is journaled in the casing in diagonally opposite relation to the roller 10, and opposite to the roller 8. A roller 12 is journaled in the casing and is located between the rollers 9 and 11. All of the rollers 8, 9, 10, 11 and 12

are vertically disposed. A chart in the form of a broad tape 14 is provided. The tape 14 is wound at its ends about the rollers 8 and 9. The tape 14 is extended about the roller 10, and then across the interior of the casing 1, as shown in Figure 4, the tape passing about the roller 12, and about the roller 11 to the roller 8. Figure 2 shows that there is a vertical scale 15 on the outside of the casing 1, the scale reading downwardly, and being located adjacent to one edge of the large opening 5. The tape or chart 14 moves horizontally across the opening 5. As shown in Figure 7, there are vertical lines of numerals 16, on that tape or chart 14. The lines of numerals shown at 16 are adapted to be exposed one at a time through the opening 5. A narrow tape or chart 17 is located above the broad tape 15 and is mounted on the rollers 8, 11, 12, 9 and 10 as shown in Figure 4 in connection with the tape 14. Any suitable means 18 may be provided, for rotating the rollers 8 and 9, so as to cause the tapes 14 and 17 to move horizontally, thereby to cause the lines of numerals 16 on the tape 14 to register with the opening 5, and to cause the numerals 100 on the tape 17 to register with the opening 6. The numerals 100 on the tape 17 represent the price per gallon of gasoline, whereas the numerals in the lines 16 on the tape 14 indicate the prices of the various quantities of gasoline shown by the scale 15 on the casing 1. The numerals in the lines on the tape 14 are aligned horizontally with the various graduations of the scale 15. The tapes 14 and 17 move in consonance and there is a line of numerals 16 on the tape 14 for each of the numerals 100 on the tape 17.

The numeral 19 marks a flexible screen or curtain which moves vertically in operative relation to the horizontally movable tapes 17 and 14. The screen or curtain has openings 20 which expose, one at a time, the numerals 16 on the tape 14 at the respective sides of the casing 1. In its intermediate portion, the screen or curtain 19 is formed into a bight 21. One side of the bight 21 passes downwardly around the horizontal roller 22 journaled on the casing 1 at the bottom thereof. From the roller 22, the curtain or screen 19 passes upwardly in front of the broad tape 14, and behind the narrow tape 17, and, thence, downwardly about a guide roller 23 mounted horizontally

in the casing 1 at the upper end thereof. The opposite side of the bight 21 is extended horizontally beneath a horizontal guide roller 24 journaled on the casing 1, and thence 5 upwardly around a guide roller 25 similarly supported, the screen or curtain passing upwardly to and about a guide roller 26 mounted horizontally in the upper portion of the casing 1. The free ends of the 10 screen or curtain 19 carry weights 27.

The bight 21 in the curtain or screen 19 is connected to a yoke 28 with which is united the lower end of a flexible element 29, extended upwardly about a vertical sheave 30 15 journaled in the top of the casing 1, and thence, about a horizontal sheave 31 likewise supported in the top of the casing, the flexible element being extended through the tubular guard 4 and about a drum 32, the 20 flexible element being connected to the drum 32. The drum 32 rotates with a drum 33, the drums 32 and 33 being rotatable on a shaft 34 carried in the upper portion of the measuring tank 3. A flexible element 36 is 25 wound at one end about the drum 33 and is secured thereto. The flexible element 36 extends downwardly into the measuring tank 3 and is connected to a float 35 cooperating with the liquid 50 in the measuring tank 3. 30 The diameter of the drum 32 remains unchanged, but drums of different diameters may be substituted for the drum 33, depending upon the distance that the float 35 has to move in the measuring tank 3. Not every 35 measuring tank has a float like the float 35, and it will be understood that the flexible element 36 may be connected to any kind of a mechanism which is responsive to the changes of level in the liquid in the tank 3. 40 If the measuring tank is visible and above ground, the float 35 generally is used, but if the measuring tank is below ground, or is of a different construction than that shown in the drawings, any mechanical equivalent of 45 the float 35 may be used for operating the flexible element 36.

When a predetermined amount of gasoline or other liquid is drawn from the measuring tank 3, the float 35 moves downwardly, a 50 pull is exerted on the flexible element 36, motion is transmitted by way of the drums 33 and 32, and the flexible element 29, to the bight 21 of the screen 19, the screen being caused to move vertically, and the opening 55 20 being caused to disclose the appropriate

one of the numerals 16 on the tape 14. Thus, for instance, in Figure 2, it is made evident that five gallons of gasoline, indicated on the scale 15 will cost \$1.00, if the price per gallon of gasoline is 20¢ as indicated by the 60 numeral 100 on the tape 17 which is visible through the opening 6. When the measuring tank 3 is full, the opening 20 in the screen or curtain 19 disappears out of sight behind the narrow tape 17. The rollers 8 65 and 9 may be operated by the means indicated at 18 so as to bring the appropriate line of numerals 16 on the tape 14 into registration with the opening 5 in the casing 1, and, simultaneously, to bring the proper 70 price numeral 100 on the tape 17 into registration with the opening 6. The numerals shown at 16 preferably are inscribed on both sides of the tape 14, and the rollers 10, 12 and 11 serve to reverse the tape 14, so that 75 the numerals on either side of the tape are visible at one side of the casing 1 only. The weights 27 maintain the screen 19 taut, and operate the screen, when the flexible element 29 is slackened away, and when the bight 21 80 flattens out or moves downwardly.

What is claimed is:—

A mechanical movement including a frame, horizontal lower guides on the frame, horizontal upper guides on the frame, a first 85 flexible element extended between the lower guides, thence upwardly to form side portions which are extended downwardly about the upper guides to define free depending ends located between the side portions, 90 weights on the depending ends of the first flexible element, an upwardly extended operating device connected to the first flexible element at a point between the lower guides and mounted slidably upon the upper portion of the frame, a horizontally disposed second flexible element extended in opposite directions across the side portions of the first flexible element at right angles thereto, the second flexible element being extended between the side portions of the first flexible element, means for supporting the second flexible element in position, and means for moving the second flexible element endwise with respect to the side portions of the first 100 flexible element.

In testimony that I claim the foregoing as my own, I have hereto affixed my signature.

WILLIAM EDWARD TRAYLOR.
